UNITED STATES PATENT OFFICE.

FRANK R. MCBERTY, OF EVANSTON, ILLINOIS, ASSIGNOR TO THE WESTERN ELECTRIC COMPANY, OF CHICAGO, ILLINOIS.

SELECTIVE CALLING-KEY FOR PARTY-LINES.

SPECIFICATION forming part of Letters Patent No. 680,881, dated August 20, 1901.

Application filed January 6, 1900. Serial No. 532. (No model.)

To all whom it may concern:

Be it known that I, FRANK R. MCBERTY, a citizen of the United States, residing at Evanston, in the county of Cook and State of Illinois, have invented a certain new and useful Improvement in Selective Calling-Keys for Party-Lines, (Case No. 83,) of which the following is a full, clear, concise, and exact description.

10 My invention relates particularly to systems of telephone-exchange in which party-lines are employed. In such systems it is usual to place four stations upon one telephone-circuit, the bells of two stations being connected with one limb of the circuit and the bells of the other two stations being connected with the other limb thereof, each bell being in a normally-grounded branch. The bells are polarized and adapted to respond to 15 currents of the proper direction.

20 My invention relates more particularly to the operator's selective calling-key, one such key being combined with a set of connecting cords and plugs. Each pair of cords will be provided with the usual calling-key, and when the calling-key of any particular pair of cords is pressed connection is made with the common or selective calling-key. In case the pair of cords is used for making connection with a line not a party-line the contacts of the selective calling-key being in their normal position will permit alternating current from the generator to be thrown to the line called for. Thus the operation of an individual calling-key serves to transmit an alternating current over the line. If, however, a subscriber upon a party-line is being called, the selective calling-key must be brought into service to throw current of the proper polarity onto the limb of the telephone-circuit with which the bell of the subscriber wanted is connected.

25 My invention relates more particularly to the construction of the selective calling-key and the combination thereof with the other parts of the apparatus.

30 Stated generally, the selective calling-key consists of four double sets of contact-springs grouped about a central standard or axis, upon which is mounted by a ball-and-socket joint the operating-lever, said lever carrying

35 four radial arms, which arms are adapted each to be inserted between a particular set of springs, according to the direction in which the lever is moved, to wedge or move the springs, and thus to make and break the contacts of the different sets of keys as required. The lever is provided with a handle adapted to be moved sidewise in either of four directions to bring the proper one of the radial 40 arms or wedges against a particular spring or set of springs. An escutcheon carried by the handle of the lever when moved serves to prevent dust from getting into the contacts of the keys. When the lever is in its upright 45 position, the several sets of keys will be closed and the generator of alternating current will be connected through the said contacts, so that when the key of any particular set of cords is depressed the alternating current 50 may be thrown to line, if desired.

55 My invention is illustrated in the accompanying drawings, in which—

60 Figure 1 is a plan view of my selective calling-key. Fig. 2 is a side elevation thereof. Fig. 3 is a side view, partially in section, certain parts being removed. Fig. 4 is a plan view of the sets of keys as seen from line 2 65 Fig. 2, Fig. 2. Fig. 5 is a view as seen from section-line 3 3, Fig. 3; and Fig. 6 is a diagram 70 illustrative of a four-party-line circuit and the connections of the operator's apparatus with my selective calling-key.

75 Like parts are indicated by similar characters of reference throughout the different 80 figures.

85 I will first refer to the party-line circuit shown in Fig. 6. This circuit consists of two limbs a b . The bell a' of station 1 is connected in a grounded branch with said limb a and adapted to respond to positive current. The bell a^2 of station 2 is connected in like manner with said limb a , but adapted to respond only to negative current. Bell b' of station 3 is connected in a similar way with limb b , as well as bell b^2 of station 4, bell b' being polarized to respond to + current and bell b^2 to respond to - current. A source of current c is provided at the central office, and heretofore it has been common to send 90 current of proper polarity from such a source over the different limbs a b of party-lines of

the character described. The generator *d* is an ordinary source of alternating current. When the ordinary key *e* is operated or pressed, the springs *e' e* are thrown upon the 5 contacts leading to the generator *d* through the several contacts of the selective calling-key when the calling-key is in its normal position. In such case the calling-key is for the time ignored, the plug *e* being inserted 10 into some single party-line, upon which the subscribers' apparatus is adapted to respond in the usual way to alternating currents. The different sets of keys *f' f² f³ f⁴* may be considered as corresponding, respectively, 15 with the several stations 1, 2, 3, and 4 of the party-line.

As shown in detail in Figs. 1 to 5, the selective calling-key consists of four double sets of springs *f' f² f³ f⁴*, arranged centrally 20 about the standard or axis *g*. Upon this standard *g* is mounted the lever *g'*, having the ball-and-socket joint *g²* and carrying the radial arms or wedges *h' h² h³ h⁴*. When the lever is in its normal position—that is, upright, as shown in Fig. 2—the contacts of the different springs will be as illustrated in Fig. 25 6. When it is desired to open the normal contacts of a particular set of springs for the purpose of throwing calling-current onto the line, it is only necessary to tilt the lever in the direction required. For example, as shown in Fig. 3, the arm or wedge *h'* is thrust 30 between the springs *i i'*, in which case the spring *i* will be thrown upon the anvil or contact *k* and the spring *i'* upon the anvil or contact *k'*. Thus in this particular instance the plug *e* being inserted in spring-jack *l* corresponding thereto + current will be sent over limb *a* and passing through bell *a'* of station 1 35 40 will operate the same. In like manner the lever may be thrown to operate the keys *f² f³ f⁴* to ring the bells at the other stations 2, 3, and 4 of the party-line as desired.

The escutcheon *m* is placed over the convex 45 plate *m'* and is held against said plate, so as to prevent dust from entering, by means of the spring *m*.

Having thus described my invention, I claim as new, and desire to secure by Letters 50 Patent, the following:

1. The combination with the double sets of contact-springs *f' f² f³ f⁴*, of the centrally-placed standard or axis and the lever pivotally mounted on said standard, said lever carrying radial arms or wedges *h' h² h³ h⁴*, one 55 for each set of springs; whereby the contacts of said sets of springs may be changed on tilt-

ing the lever, substantially as and for the purpose specified.

2. The combination with the pivoted lever *g'*, of two or more radial arms or wedges mounted thereon at right angles to one another, and sets of contact-springs, one for each of the said arms, said sets of springs being arranged about the axis or support of the said lever, 60 the arm or wedge of a particular set of springs being adapted to be forced between the members of such set to wedge the same apart and change the contacts thereof on tilting the lever in the proper direction. 70

3. The combination with a number of sets of contact-springs arranged around a central standard, of an operating-lever pivotally mounted on said standard and adapted to be tilted angularly in different directions to actuate any desired set of contact-springs, a convex plate *m'* through which the handle of the lever is passed, having an opening in which said lever may be moved to and fro, and a convex escutcheon *m* carried by the lever and fitting over said opening in the convex plate, substantially as set forth. 75

4. The selective calling-key consisting of vertically-placed switch-springs grouped about an axis or standard, in combination 80 with wedges of insulating material adapted to be moved by a common lever, the center of pressure or greatest resistance of the springs to the wedges when thrust between them being above the pivotal bearing of the support 85 for the wedges; whereby the resistance of the springs of any set when a wedge is forced between the same aids in keeping the support for the wedges against its bearing, substantially as and for the purpose specified. 90

5. The pivoted operating-lever with four radial arms therefrom at right angles to each other and to the lever, carrying-wedges, in combination with the four sets of switch-springs, one adapted to be operated by each 95 wedge, and the central standard *g* supporting the lever at the center of the four arms, whereby two wedge-arms in alignment with one another rotate as a shaft between the corresponding switch-springs while a wedge at 100 right angles thereto is thrust between the springs to operate them, substantially as set forth. 105

In witness whereof I hereunto subscribe my name this 11th day of November, A. D. 1899. 110

FRANK R. MCBERTY.

Corrections in Letters Patent No. 680,881.

It is hereby certified that in Letters Patent No. 680,881, granted August 20, 1901, upon the application of Frank R. McBerty, of Evanston, Illinois, for an improvement in "Selective Calling-Keys for Party-Lines," errors appear requiring the following corrections: The drawings forming a part of said patent should have been corrected, as directed by the patentee in an amendment duly filed before the issue of the patent, as follows: Fig. 1, reference figures "1, 2, 3, 4" should read 2, 1, 4, 3, respectively; Figs. 2 and 3, reference letters "f' f'" should read f² f'; Figs. 2 and 3, reference letters "h' h'" should read h³ h'; Fig. 3, reference letter "i" should be stricken out, and the spring on the left-hand of the drawing should be indicated by i'; Fig. 4, reference letters "i' i'" as applied to the right-hand set of springs should be stricken out and inserted to indicate the left-hand set, and letters "h' h² h³ h⁴" should read h³ h⁴ h' h², respectively, and Fig. 5, reference letters "i' k'" should be stricken out, and f' f² f³ f⁴ should be inserted to indicate the different sets of keys; i' to indicate the springs, and k' to indicate the anvils or contacts; and that the said Letters Patent should be read with these corrections therein that the same may conform to the record of the case in the Patent Office.

Signed, countersigned, and sealed this 10th day of September, A. D., 1901.
